UNITED STATES PATENT OFFICE

ALFRED E. LUDERS, OF STAMFORD, CONNECTICUT

SAIL

Application filed May 23, 1930. Serial No. 454,936.

This invention relates to sails for vessels and more particularly to a kind of sail known as a spinnaker, being a long approximately triangular sail frequently employed opposite 5 a main sail on a yacht when it is sailing before the wind.

I have discovered that if I cause such a sail to materially distend intermediately, or "bag" toward the front and sidewise, I can 10 increase the effect of the wind thereon, and thereby increase the speed of the vessel. I prefer to effect the desired "bagging" by 15 gathering the edges of the sail so that it does not naturally lie flat, but in a sort of pouch form. To prevent such gathering from 20 puckering the sail edges and interfering with the handling of the same, I first form V-shaped notches in the sail edges and then bring the sail cloth together on opposite sides 25 of such notches so that the perimeter or boundary along the luff and leech and bottom of the sail is materially reduced over that of an ordinary sail of originally the same size. This causes the intermediate region of the sail to bow forwardly and sidewise to a very decided extent.

While I can make the V-shaped recesses in a sail as ordinarily constructed—that is, with different strips of cloth all parallel to 30 each other—I prefer to arrange the strips so that the seams are approximately at right angles to the luff, leech and bottom. Thus, the V-shaped notches are made at the ends 35 of such seams, and then when the sewing of the sail cloth is finally completed the sides of the V-notches come together to produce a 40 continuation of the seam and a smooth fabric surface is produced but with a very materially reduced boundary and a pronounced bagging.

My invention is hereinafter more fully explained in connection with the illustrations in the drawings, and the essential novel features are summarized in the claims.

In the drawings, Fig. 1 is a side elevation 45 of a sloop-yacht with my spinnaker set; Fig.

2 is a view of the sail cloth of the spinnaker as originally cut and seamed, but before the sewing at the notches is effected; Fig. 3 is a view on the same scale of this spinnaker after the notches are brought together, illustrating the reduction in size by reason of the gathering together of the boundary edge; Figs. 4 and 5 are diagrams illustrating respectively a longitudinal section and a transverse section of the ordinary spinnaker and 55 of my spinnaker having the same amount of cloth.

In Fig. 1, A indicates a suitable sloop-yacht having a mast B which is shown as carrying usual sails, as for instance main sail C, top 60 sail D and balloon jib E attached at its lower end to the bow sprit F. In this figure G indicates my spinnaker, which is attached at its upper end, at g, to the mast, and at one lower corner secured by a clew H. At the 65 other corner it is secured to a light spinnaker boom J stepped onto the mast and held by a suitable sheet K, or set flying from a rope or sheet, dispensing with the spinnaker boom.

This view is somewhat conventional, but is 70 intended to indicate the position of the spinnaker when the vessel is sailing before the wind, the direction of which is indicated by the arrow.

Fig. 2 indicates the sail cloth of my spinnaker G before the edges are gathered. It will be seen there is a central longitudinal seam 10 which extends from the top of the sail to a point 11 which is about equi-distant from the luff and leech edges and from the bottom. From this point the seam divides and passes as two miter seams 12 and 13 leading from the point 11 to the point where the bottom joins the luff or leech edge. The inner ends of the fabric strips 15 terminate at the 75 respective main seams and extend outwardly at approximately right angles to the adjacent boundary edge, the successive widths of fabric being joined by seams as 16 which terminate 80 some distance from the outer edge. Adjacent 85

90

the outer edge, V-shaped notches 17 are made in registration with the seams 16. This gives a fabric structure in a plane of the form indicated in Fig. 2, and indicated in vertical 5 and transverse section by the straight lines X and Y in Figs. 4 and 5.

Having formed the basis of the sail as above explained, I stitch together the opposite edges of each V-shaped notch, thus materially reducing the boundary 18 and bringing 10 the sail into the bag-like form shown in Fig. 3, this form being also indicated by the vertical and transverse sections X1 and Y1 respectively in Figs. 4 and 5. Suitable hems, with 15 or without embedded cords, may be employed at the edges, as desired.

Experiments which I have made with a spinnaker produced as above described, show that such sail is more effective in driving the 20 vessel than an ordinary spinnaker. This advantage may be due to the fact that the bag-shape retains the wind more effectively than heretofore, or it may be that it is able to catch wind which is not directly from the 25 stern, or it may be that when the bag fills with wind it presents a greater area thereto than with the flat sail of the same perimeter. Apparently this arrangement also enables the 30 top part of the sail to perform a greater portion of the work than heretofore, and experience has demonstrated that the top portion 35 is the most efficient region of the sail in driving a vessel.

I claim:—

35 1. A substantially triangular sail having 100 its edges periodically gathered to materially reduce the boundary.

2. A sail made of fabric strips stitched together and having notches at its edges which 40 are thereafter closed to reduce the boundary 105 length of the sail.

3. A sail made of fabric strips stitched together and having inwardly pointing V-shaped notches at its edges the boundaries of 45 which are thereafter brought together to reduce the perimeter of the sail.

4. A sail having fabric strips stitched together by seams, which seams lead toward the boundary of the sail, the sides of the strips 50 being cut away at the boundary in registration with the seams to provide V-shaped notches which are thereafter closed.

5. A spinnaker made up of fabric strips 55 extending at approximately right angles to its luff, leech and bottom edges, the strips of fabric between the seams being narrowed at such edges and the adjacent strips being joined together along their edges.

6. A sail having a main central seam 60 extending from its top and to an intermediate region and having two main seams extending from such point to the corners where the bottom joins the other two edges, the fabric strips forming the sail terminating at their inner ends at such main seams and extending

outwardly to the sail edges, the outer portions of such strips being cut off at opposite sides to leave V-shaped notches registering with the seams between the strips, and the opposite sides of the notches being brought together, whereby a bag is produced. 70

7. A new and improved spinnaker, comprising a fabric sheet gathered in various regions of its luff, leech and bottom edges to form a wind trap. 75

In testimony whereof, I hereunto affix my signature.

ALFRED E. LUDERS.
